UNITED STATES PATENT OFFICE.

ORA A. COLBY, OF IRWIN, PENNSYLVANIA, ASSIGNOR TO WESTINGHOUSE ELECTRIC & MANUFACTURING COMPANY, A CORPORATION OF PENNSYLVANIA.

ELECTRIC TOOL-TEMPERING FURNACE.

Application filed May 4, 1920. Serial No. 378,790.

To all whom it may concern:

Be it known that I, ORA A. COLBY, a citizen of the United States, and a resident of Irwin, in the county of Westmoreland and State of Pennsylvania, have invented a new and useful Improvement in Electric Tool-Tempering Furnaces, of which the following is a specification.

My invention relates to electric furnaces and particularly to furnaces of the electric-resistance type and it has for one of its objects to provide a furnace which may be operated continuously for comparatively long periods of time at a relatively high temperature for tempering steel dies and for heating and heat-treating metals.

Another object of my invention is to provide a furnace resistor which shall have a relatively slow rate of deterioration and which may be easily and quickly replaced in case it becomes damaged during the operation of the furnace.

Another object of my invention is to provide means for simultaneously heating both sides of metal dies placed in a furnace of the above-designated character.

In practicing my invention, I provide a chamber in a refractory casing, the chamber having an arched roof, resistors comprising solid blocks of refractory electrical-conducting material located adjacent to the sides of the chamber and other resistor blocks located in the floor of the chamber. I provide wells or hoppers in the casing adjacent to the ends of the resistor blocks and place therein a mass of electrical-conducting granular material which is adapted to conduct the current to and from terminal electrodes which project into the wells.

Referring to the single sheet of drawings, Figure 1 is a top plan view of a furnace embodying my invention; Fig. 2 is a cross-sectional view of the same furnace along the line II-II of Fig. 1, and Fig. 3 is a cross-sectional view of the furnace along the lines III-III of Fig. 2.

The supporting structure of the furnace comprises an exterior metal casing or frame 1 in which is placed an outer shell 2 of heat-insulating brick and an inner shell 3 of fire brick. The fire brick 3 are spaced apart to provide a chamber 4 substantially in the middle of the furnace, the chamber being provided with an arched roof 5 made of suit-

able highly-refractory material adapted to withstand high temperatures.

A main resistor 6 comprises bricks or slabs of refractory electrical-conducting material, such as carborundum or silicon carbide, each brick having a substantially rectangular cross-section. Each of the two resistor blocks 6 is located in a substantially V-shaped trough 7 formed in the shell 3, its larger face being so located as to radiate heat against the concave surface of the roof from which the heat will be reflected downwardly upon the material to be heat treated.

A plurality of blocks 8 of resistance material, similar to the resistor blocks 6 but of somewhat smaller cross-sectional area, are located in the floor of the chamber 4, being held in their proper operative position by suitable spacing members 9, which may consist of fire brick similar to that used in the inner shell 3. While I have shown the resistors 8 as projecting above the floor of the chamber 4, I do not desire to be limited to this arrangement and may locate these resistors beneath the floor of the chamber or level therewith so that the resistors themselves need not carry the weight of the material being heat treated.

Opposite to, and adjacent each end of the resistor blocks 6 and 8, the inner shell 3 is so spaced apart as to provide wells or hoppers 10 and 11 into which the ends of the resistor blocks extend. Terminal electrodes 12 extend from the outside of the furnace into the hoppers or wells 11 substantially at the lower end thereof. Each of the wells 10 and 11 is filled with a mass 13 of electrical-conducting granular material, such as graphite or coke, and this mass serves to conduct the current from the terminal electrode, which may be made of solid carbonaceous material, to the ends of the resistor blocks and, in the case of the well 10, to conduct the current from one set of resistor blocks to the other. In Fig. 1, I have shown an arrangement of terminal electrodes and hoppers which will permit the electric supply-circuit conductors 14 being located at the rear of the furnace out of the way of the operator.

One of the problems in connection with the use of solid refractory electrical-conducting material for resistors is that of a satisfactory connection to said resistors. As some oxidation of carborundum resistor blocks

always occurs during the operation of the furnace, the resistor blocks will be gradually consumed, and unless some simple means is used to maintain the contact therewith, serious arcing will occur. The use of the granular electrical-conducting material tends to prevent such arcing and provides a multitude of current paths by which the current may enter the resistor. Some oxidation of this granular material takes place during the operation of the furnace and, as the wells 10 and 11 are open at the top of the furnace, this material may be easily tamped in place to provide good operative contact with the projecting ends of the resistor blocks, and a fresh supply of such material may be easily added, as required.

I am aware that an arched roof has already been used in the furnace art to reflect the rays from a resistor located in proximity thereto, but I believe it to be new to use solid refractory material of such form and cross-section that the larger area thereof may be located in heat-radiating relation to the arched roof which then reflects the rays upon the floor of the chamber to heat the same prior to the insertion of the metal die to be tempered or radiates the heat upon the metal die itself. I believe it to be also new to provide an auxiliary resistor located in the floor of the chamber to furnish heat to the lower side of the metal die when the same is placed in the chamber as, of course, the floor of the chamber is precluded from receiving any radiated heat as soon as a metal die of relatively large area is placed in the chamber to be heat treated.

While I have shown a specific embodiment of my invention, various changes may be made therein without departing from the spirit and scope of my invention and I desire, therefore, that only such limitations shall be placed thereon as are imposed by the prior art or are specifically set forth in the appended claims.

I claim as my invention:

1. In an electric furnace, the combination with a chamber and a concave roof for said chamber, of a plurality of resistors comprising solid blocks of refractory electrical-conducting material of rectangular cross-section, one of the larger faces of said blocks being so located as to radiate heat against said concave roof, a plurality of hoppers at the rear of said furnace opposite the rear ends of said resistor blocks, a hopper at the front of said furnace opposite the front ends of said resistor blocks, solid terminal electrodes in said hoppers at the rear of said

furnace and a mass of electrical-conducting granular material in said rear hoppers interposed between said electrodes, and said resistors and adapted to conduct the current therebetween and to prevent overheating of said electrodes, and a mass of electrical-conducting granular material in said front hopper adapted to conduct current between said resistors.

2. In an electric furnace, the combination with a chamber and a concave roof for said chamber, of a main resistor comprising solid blocks of electrical-conducting material of rectangular cross-section located at the sides of said chamber, one of the larger faces of said blocks being so located as to radiate heat against said roof, an auxiliary resistor comprising solid blocks of electrical-conducting refractory material located at the bottom of said chamber, hoppers adjacent the ends of said resistors, electrodes in said hoppers and a mass of electrical-conducting granular material in said hoppers interposed between said electrodes and said resistors, the cross-section of said mass of material being greater than the cross-section of the resistors to prevent overheating said electrodes.

3. In an electric furnace, the combination with a chamber and a concave roof for said chamber, of a main resistor comprising solid blocks of refractory electrical-conducting material located at the sides of said chamber and adapted to heat one side of an object placed in said chamber by heat reflected from said roof, and an auxiliary resistor comprising solid blocks of refractory electrical-conducting material located in the floor of said chamber and adapted to support an object placed in said chamber and to heat the under side thereof.

4. In an electric furnace, the combination with a chamber and a concave roof for said chamber, of a main resistor comprising solid blocks of refractory electrical-conducting material located at the sides of said chamber and adapted to heat one side of an object placed in said chamber by heat reflected from said roof, hoppers located opposite the ends of said blocks, and a mass of electrical-conducting granular material in said hoppers adapted to conduct current from and to said resistor blocks and of greater cross-section than said resistor blocks to prevent overheating of said masses.

In testimony whereof, I have hereunto subscribed my name this 19th day of April, 1920.

ORA A. COLBY.
